A. A. HODGKINS

SHOULDER STRAP FOR WEARING APPAREL

Filed Sept. 13, 1922

FIG. 2

FIG. 1

Albert A. Hodgkins INVENTOR.

BY

Hoover & Davis ATTORNEYS.

UNITED STATES PATENT OFFICE.

ALBERT A. HODGKINS, OF BRIDGEPORT, CONNECTICUT, ASSIGNOR TO THE AMERICAN FABRICS COMPANY, OF BRIDGEPORT, CONNECTICUT, A CORPORATION OF CONNECTICUT.

SHOULDER STRAP FOR WEARING APPAREL.

Application filed September 13, 1922. Serial No. 587,946.

To all whom it may concern:

Be it known that I, ALBERT A. HODGKINS, a citizen of the United States, residing at 141 Bronx Avenue, Bridgeport, county of 5 Fairfield, State of Connecticut, have invented an Improvement in Shoulder Straps for Wearing Apparel, of which the following is a specification.

This invention relates to wearing apparel, 10 and has for an object to provide a shoulder strap for a lady's garment, which will not slip from the shoulder.

With this object in view, I have devised a shoulder strap, as illustrated in the accompanying drawing, in which—

Fig. 1 is a view showing the use of my improved shoulder strap.

Fig. 2 is a front view showing the shoulder line and the top of one side of a garment 20 with my improved shoulder strap attached and showing in dotted lines the old type of shoulder strap.

Fig. 3 is a plan view of a section of strap or ribbon according to my invention under 25 uniform tension throughout the width thereof, and

Fig. 4 shows a similar section not under tension showing the shape it will naturally assume, the amount of curvature being somewhat exaggerated for better illustration.

In the specification and claims I use the phrase "horizontal line of the garment" to mean the top 13 when the wearer is upright and this top is straight, as in that position 35 it would be substantially in a horizontal plane.

In the use of the ordinary shoulder strap, which comprises a straight piece of tape or ribbon, if it is ordinarily attached to a garment at substantially right angles to the horizontal line of the garment, it will be apparent as the strap goes substantially vertically over the shoulder and the shoulder line is inclined, that it has a high and low side 40 in comparison to the horizontal line of the garment, and the strap, if held taut, will bear on the shoulder only at the inner edge thereof, and will be spaced from the shoulder at its outer edge. Thus the entire strain 45 is on the inner edge, and as the strap tends to assume a position whereby it will lie flat on the shoulder, it will move outwardly, and slip from the shoulder.

In an attempt to overcome this objection,

straight straps, instead of being secured to 55 the garment normal to or at right angles to the horizontal line thereof, are sometimes secured nearer to the center of the garment, and at an acute angle to the horizontal line thereof. A strap secured in this manner 60 will lie flat on the shoulder, but is objectionable as the point of attachment is near the center of the body instead of near the sides, and can not be used with certain cuts of outer garments, and when used on outer garments 65 themselves does not look well.

In Fig. 2 I have shown the outline of the shoulder and a portion of the garment with these two types of straps, the old style being shown in dotted lines. In full lines, 70 and superimposed on these I have drawn my improved shoulder strap. It will be evident from this figure that my strap is secured to the garment normal to or at right angles to the horizontal line of the garment, 75 and at the same point as is the straight strap, but that as it passes over the shoulder it lies flat on the shoulder as does the inclined strap. In this Fig. 2 the straight strap is indicated by the dotted lines 7 to 8, the inclined strap is indicated by dotted lines 9 to 10, and my improved strap is indicated by full lines 8 to 9.

In Fig. 1 I have indicated how a pair of straps made according to my invention lie 85 on the shoulders, the straps being indicated by numerals 18 and 19. These straps are so designed that each will pull evenly on both of its sides when worn on the shoulder even though the line of the shoulder has a high 90 and low side in comparison to the horizontal line of the garment. This is accomplished by weaving the strap longer on one edge than on the other, so that when attached to the garment as shown, the inner edge 20 will 95 be longer than the outer edge 21, and it will thus lie flat on the shoulder line while attached at right angles to the garment.

In weaving, the warp threads at one edge are longer than at the other edge, and the 100 threads intermediate the edges are of varied lengths intermediate the lengths of the outer threads. Each thread may be a different length than each of the other threads, and increasing gradually from one side to 105 the other, or there may be a series of groups of threads with each thread of a group of the same length, but each group being of a

different length from the adjacent groups to secure the same result. This is indicated at 22 at the right hand of Fig. 3. The filling threads are spaced a slightly greater distance from each other on the side of the tape or ribbon, having the long warp threads than they are on the side having the short warp threads, so that the finished tape or ribbon, when not under tension and allowed to assume its natural position, will be curved in the plane of the ribbon as indicated in Fig. 4, and the filling threads will be substantially on the radii of the curve and at right angles to the warp threads. In Fig. 4 these filling threads are indicated at 23 and the warp threads at 24, the center of the curve being indicated at C. When, however, a uniform tension is placed on the warp threads throughout the width of the ribbon, the warp and filling threads will shift relatively to each other, and allow the ribbon to assume a straight position, as shown in Fig. 3. This effect is indicated by the light lines in Fig. 4, in which I have shown the two outer warp threads only at 25 and 26. As these threads are drawn straight from the curved positions, by striking arcs 27 and 28 with centers at 29 and 30 (on the center line of the piece of ribbon or tape) from the points 31 and 32 where, for example, a filling thread 33 intersects these warp threads, then the points 34 and 35 where the filling

thread intersects the straightened warp threads will be determined.

Having thus set forth the nature of my invention what I claim is:

1. A woven shoulder strap for wearing apparel of substantially even width with its edges parallel with the warp of the cloth and longer on one side than on the other so that when attached at substantially right angles to the horizontal line of the garment as worn it will be higher on the inner side than the outer and thus lie flat on the shoulder.

2. A garment, and a woven shoulder strap of substantially even width secured to the garment at substantially right angles to the horizontal line of the garment, the edges of the strap being parallel with the warp of the cloth and of greater length on the inner than on the outer side so that when worn it will lie flat on the line of the shoulder.

3. A garment, and a woven shoulder strap of even width secured to the garment at substantially right angles to the horizontal line of the garment, the edges of the strap being parallel with the warp of the cloth and the inner warp threads of said strap being longer than the outer warp threads so that the strap is longer on its inner edge than its outer edge.

In testimony whereof I affix my signature.

ALBERT A. HODGKINS.
